DEVICE FOR CUTTING INDEX TABS IN
BOOK PAGESWilliam J. Alvino, Massapequa, and Jacob Bauer,
Glendale, N. Y.

Application June 11, 1948, Serial No. 32,344

2 Claims. (Cl. 30—178)

1

This invention relates to improvements in devices for cutting notches in pages of books to expose the section or index tabs therein. It relates particularly to an improved form of knife or blade for use in devices of the type referred to above.

The shears used heretofore for the above-mentioned purpose are of the power actuated cutter and anvil type, that is, they include a cutter member which is urged by pneumatic pressure against an opposing flat surface formed on an arm which is inserted between the leaves of the books so that as the cutter moves, it shears off sections of the pages of the books of increasing depth from top to bottom to provide the aforementioned notches.

The knife or blade used in a device of the character described generally above is of generally semi-cylindrical or gouge-like shape and has arcuate cutting edges at its opposite ends. This blade is mounted on a cylindrical portion on one of the arms of the shears by means of a set screw and is usually provided with a slot extending lengthwise of the blade to permit adjustment of the blade toward and away from the cooperating anvil.

In order to prevent the blade from slipping endwise under cutting impact, the arm on which the blade is mounted is provided with a threaded member for receiving a nut which bears against the cutting edge at the upper end of the blade. It is intended that the blade should be reversed to allow the sharp edge to be used until it, in turn, becomes dull. Practically, the edge of the blade which is in engagement with the adjusting nut is not of any great utility for the reason that it quickly becomes dull by reason of its engagement with the nut. In addition, because of the shock to which the blade is subjected, this upper and non-used edge oftentimes is chipped or broken.

It has also been found that the prior blades become dull very quickly. It is believed that loss of sharpness is due to the fact that the corners of the blade come into contact with the anvil so forcefully that they tend to chip or crack. Also, the blade does not have sufficient transverse rigidity and, as a consequence, it vibrates on passing through the pages of the books, and this vibration not only quickly dulls the edge of the blade but it also results in score lines or ragged edges on the notches cut in the books. Usually, blades of the type used heretofore have an effective operating life, before requiring resharpening, of only two or three hours when used continuously.

Sharpening of the dull blades is a rather difficult operation requiring substantial skill because the steel used in these blades is very hard and the bevel on the blade must be ground to close limits. As a result, the frequent replacement and re-

2

sharpening of the blades is expensive and time consuming.

An object of the present invention is to provide an improved form of cutting blade for shears for notching book pages which can be used for long periods of time without resharpening.

Another object of the invention is to provide an improved form of blade or knife for devices of the type described above which is much less likely to break and which can be more firmly and securely retained in position so that tearing or scoring of the edges of the notches in the pages is, to a large extent, eliminated.

Further objects of the invention will become apparent from the following description of a typical form of knife or blade embodying the present invention.

In accordance with the present invention, we have provided a blade for cutting notches in the pages of books and the like in which the cutting edge is annular or circular. The blade is further characterized by a semi-cylindrical hollow body portion which adapts it to fit over the positioning head or hammer of the conventional type of shear used in notching operations. The blade is further provided with an annular sleeve portion at its upper end which receives the head of the hammer to thereby more securely position the blade on the shear arm.

Blades of the character embodying the present invention have been found to have a much greater operating life without resharpening than any of the prior types of blades. The new blades have been operated for periods of several weeks without requiring sharpening for apparently the cutting operation causes an automatic sharpening of the blade. Moreover, breakage of the blades due to impact is reduced to a minimum.

For a better understanding of the present invention, reference may be had to the accompanying drawing, in which:

Fig. 1 is a view in side elevation of a typical form of notching shears provided with a blade of the type embodying the present invention.

Fig. 2 is a view of the head or hammer of the shears with the new blade mounted thereon and disclosed in longitudinal section; and

Fig. 3 is a view in elevation looking toward the back of the blade.

The new form of blade will be described as used in conjunction with cutter and anvil types of shears of the kind commonly used for notching the pages of books. As shown in Fig. 1, the shear mechanism includes a handle portion 10 having a forwardly projecting arm 11 which is provided with a tapered nose portion 12 of generally wedge shape which adapts it to be inserted between the pages of a book. The nose portion 12 is provided with an anvil 13 which may be of disc-like form

formed of a hard plastic material which is secured to the arm 11 by means of a rivet or screw. Piv-

totally mounted at 14 on the lever 11 is a second lever 15 which is provided with a head or hammerlike portion 16 on which the cutter is supported. The lever 15 has a rearwardly projecting arm 17 which is connected by means of a link 18 to a piston rod 19 which in turn is pivotally connected to a piston 20 of a pneumatic jack 21. The cylinder 22 of the jack is supported rigidly on the lever 11 by means of a downwardly extending bracket 23 so that the handle 10 and the cylinder 19 are maintained in fixed relation to each other. The lower end of the link 18 and the outer end of the piston rod 19 are connected by means of a link 24 to the right-hand end of the handle 10.

Air may be supplied to the cylinder 22 by means of a pipe 25 which is connected to the cylinder through a valve 26, the details of which are not shown. The valve 26 is opened and closed by means of a plunger 27 to admit air into the cylinder and to discharge air from the cylinder through a pipe 28 which blows the severed portions of the paper from the anvil 13. In operation, when the plunger 27 is depressed, the piston 20 moves to the right, thereby rocking the link 24 which controls the movement of the right-hand end of the piston rod 20 and also straightens the link 18 with the result that the lever 15 is rocked counterclockwise to urge the head 16 toward the anvil 13. Upon release of the plunger 27, air is vented from the cylinder through the pipe 28 and the elements are returned to the position shown by means of the spring 29 which is connected at its opposite ends to the link 24 and to the lever arm 11. All of the above-described construction is conventional.

The blade which constitutes the present invention is shown in Figs. 1, 2 and 3. The blade B is provided with a tubular or annular portion 30 which is adapted to be disposed adjacent to the anvil 13. The outer surface of the edge portion 30 may be ground down to provide a bevelled cutting edge. Directly adjacent to and integral with the cutting edge portion 30 is a semi-cylindrical portion 31 of concavo-convex cross-section, so shaped and dimensioned as to fit around the cylindrical portion 32 of the hammer 16. The semi-cylindrical portion 31 extends only about half way around the cylindrical portion 32 of the hammer 16 and is relieved at its lower end so as to permit the blade to be applied to the head of the hammer.

The upper end of the blade B is provided with a sleeve 33 which fits over the upper end of the cylindrical portion 32 of the hammer 16 so that when the blade is dropped over this portion 32, it is retained rather firmly in position. The portion 32, may, if desired, be arranged so that it can be moved relative to the end of the lever 15 to permit proper adjustment of the blade as a whole with respect to the anvil 13. The upper end of the sleeve 33 is provided with an in-turned flange 34 bearing against the upper end of the cylindrical portion 32 to limit the downward movement of the blade as a whole. The blade may be held in its adjusted position by means of a nut 35 threaded on a stud 36 which extends upwardly from the arm 15 of the lever and may be also used to position the cylindrical portion 32 thereon.

The blade is further provided with an elongated slot 37 for receiving a screw 38 which is threaded into the member 32 to lock the blade in position.

The blade B is positioned accurately with re-

spect to the anvil 13 and is secured tightly in position by means of the nut 35 and the screw 38 so that vibration of the blade as a whole is reduced to a minimum. Also, the thinnest and weakest portion of the blade is supported by the cylindrical hammer portion 32 so that a very firm support for the cutting edge portion 30 is provided.

Blades of the type described above have a greatly prolonged operating life and they need be sharpened only at infrequent intervals. Apparently, these advantages of the blade arise by reason of the fact that a completely circular edge has far greater strength and rigidity and resistance to chattering under impact than does an arcuate blade edge and also the greater rigidity of the blade prevents chattering or vibration which would tend to weaken the hardened steel. Moreover, reduction of vibration permits a honing action to take place during the cutting operation so that the blade is kept sharp and the notches are cut much more cleanly in the pages of the book.

It will be understood that the blade may be varied in size and may be adjusted as the purpose demands without departing from the invention. Moreover, the shape of the cutting edge, that is, its diameter, may be modified substantially depending upon the size of the notches to be cut. Therefore, the form of the invention described above should be considered as illustrative and not as limiting the scope of the following claims.

We claim:

1. A blade for shears having a pair of pivotally connected arms, one provided with an anvil surface and the other with a generally cylindrical member having its axis disposed at substantially a right angle to said anvil portion; said blade comprising a hollow, semi-cylindrical body portion adapted to fit against one side of said cylindrical member, an annular cutting edge portion at one end of said body portion for cooperation with said anvil, a sleeve on the opposite end of said semi-cylindrical portion adapted to receive and fit the end of said cylindrical member to position said blade on said member, and a slot extending lengthwise of said body portion for receiving means to secure said blade to said cylindrical member.

2. A blade for shears having a pair of pivotally connected arms, one provided with an anvil surface and the other with a generally cylindrical member having its axis disposed at substantially a right angle to said anvil portion; said blade comprising a hollow, semi-cylindrical body portion adapted to fit against one side of said cylindrical member, an annular cutting edge portion at one end of said body portion for cooperation with said anvil, a sleeve on the opposite end of said semi-cylindrical portion adapted to receive and fit the end of said cylindrical member to position said blade on said member, and means to secure said blade to said cylindrical member.
